CLOSING MACHINE

Ronald E. J. Nordquist and John Daniel Le Frank, Maplewood, N. J., assignors to American Can Company, New York, N. Y., a corporation of New Jersey

Original application July 30, 1932, Serial No. 627,084. Divided and this application November 27, 1933, Serial No. 700,012

6 Claims. (Cl. 192—129)

The present invention relates to a machine or apparatus for sealing or closing containers, and has particular reference to manual controls for the starting and stopping mechanism. This is a 5 division of our application Serial No. 627,084, filed July 30, 1932, on Vacuum closing machine.

An object of the invention is the provision of a manual control for starting and stopping a container handling apparatus or the like through 10 actuating power element such as an electric motor, such control permitting starting of the motor only when there is no apparatus load on its shaft and further insuring the building up of proper speed of rotation for the motor before the load 15 of the machine can be transferred to it.

Numerous other objects and advantages of the invention will be apparent as it is better understood from the following description, which, taken 20 in connection with the accompanying drawings, discloses a preferred embodiment thereof.

Referring to the drawings:

Figure 1 is a top plan view of a preferred form of apparatus embodying the present invention;

Fig. 2 is a combination side elevation and sectional view of the parts illustrated in Fig. 1 being taken substantially along the broken line 2—2 in that figure;

Fig. 3 is a front elevation of the starting lever, as viewed from a position indicated by the 30 broken line 3—3 in Fig. 1;

Fig. 4 is a transverse sectional detail taken substantially along the line 4—4 in Fig. 2;

Fig. 5 is a small scale plan sectional view illustrating container feeding turrets and seaming 35 heads of the machine, taken substantially along the line 5—5 in Fig. 2; and

Fig. 6 is a wiring diagram of the electrical circuit for the motor.

The apparatus, illustrated in the drawings as 40 a preferred embodiment of the invention, comprises a fully automatic machine, the main or principal features of which are indicated and in which filled open top containers and container covers are introduced into a chamber from a suitable source of supply and presented to a sealing mechanism positioned within the chamber where they are hermetically sealed.

All of the moving parts of the various units of the machine may be driven by connection with a 50 main shaft which constitutes the driven element in the instant invention and which is continuously rotated during the normal operation of the machine by connection with an electric motor.

The driving connection from the motor to the main shaft is made through a friction clutch

which is mechanical in its operation and one of its uses is to allow manual control of the starting and stopping of the apparatus. Provision is made for preventing the starting of the motor if the clutch is in position to establish driving connection between the main and motor shafts. This feature prevents the motor picking up a load when starting from a dead stop and further prevents the load of operation of the machine being transferred to the motor until after it has attained sufficient speed. These parts of the machine are shown in some detail.

The machine illustrated in the drawings comprises broadly a main frame or housing 11 (Fig. 2) enclosing a chamber 12 in which most of the can and cover conveying and seaming mechanisms are located, a housing cover member 13 being positioned on and bolted to the top of the housing providing a suitable closure therefor and a support for the driving mechanism.

All of the operating parts of the machine are preferably motor actuated and a consideration will first be had of the motor and its driving connections through the friction clutch just referred to. The housing cover 13 directly supports an electric motor 21 (Fig. 1) and for this purpose a base plate 22 is mounted upon and secured by bolts 23 to the cover. This base plate provides a support for feet 24 formed on the motor frame, bolts 25 holding the motor in secure position. A motor shaft 27 extends toward the rear of the apparatus and carries a sprocket 28 over which operates a chain 29 also passing over a sprocket 31 (see also Fig. 2) associated with a mechanical friction clutch broadly indicated by the numeral 33.

The sprocket 31 is pinned to an outer shell 35 of the clutch and this shell is rotatably mounted upon a power shaft 36 and carries the usual inner sliding disc and disc plates of a suitable 40 multiple plate friction clutch some of the friction parts being associated with an outer sleeve member 38 feathered on the outer end of the shaft. This member 38 is encircled by a spring 39 which is confined between an inner wall of 45 the sleeve member and a nut 42 threadedly engaged on the outer extremity of the power shaft.

Parts of the friction clutch 33 including the sleeve 38 have slight longitudinal movement on the shaft 36 and when in one position and under 50 the action of the spring 39 effect engagement of the clutch. Disengagement of the clutch elements is made by a reverse longitudinal movement of these parts, accompanied by a compression of the spring 39, this being a usual con-

40

45

50

55

struction in multiple plate clutches of this general type. This moving of the parts and the resulting clutching and unclutching is under the manual control of the operator as will be hereinafter described.

The power shaft 36 is journaled in roller bearing units 51 (Fig. 2) carried in a housing cover extension 52 which rests upon and is bolted at 53 to a tubular member 54 which may be a part 10 of the container handling apparatus. An extension cap 51 (see also Fig. 1) rests upon the upper end of the housing cover extension and these two members provide a housing for the shaft and certain gears associated with it.

15 The shaft 36 within this gear housing carries a bevel pinion 58 which is keyed to the shaft and is held longitudinally against the rotatable part of the bearing unit 51 by locknuts 59 threadedly connected with the shaft. This pinion 58 20 meshes with a bevel gear 62 carried on the upper end of a main vertical shaft 63.

The shaft 63 is representative of the driven elements which are to be actuated by the motor 21 through the friction clutch 33. This shaft is mounted for rotation in any proper manner 25 within the tubular member 54 and the main frame 11, bearings 65 contained in a supporting cup 66 within the tubular member being illustrated as a bearing for the top end of the shaft. 30 Normally throughout the operations of the machine the motor 21 continually operates and rotates the sprocket 31 and if the clutch 33 is in clutched position, also rotates the power shaft 36 and the main shaft 63.

35 When the can handling apparatus is a can closing machine as shown in the drawings, filled containers with their loosely applied covers are conveyed to a seaming mechanism for uniting or double seaming the cover to the container. A transfer turret 71 (Figs. 2 and 5) is located within the chamber 12 and is used in this transfer of the containers. This turret is shown as revolving around the center of the shaft 63 which may be used in its rotation. This feature is not a part of the present invention and further description is thought to be unnecessary.

The turret 71 may comprise an upper disc 73 and a lower disc 74 both mounted on a stationary column 75 surrounding the main shaft. The two discs are provided with aligned pockets 78, 79 adapted to receive and hold a filled container 85 having a loosely applied cover 86. The turret moves in a clockwise direction as viewed in Fig. 5.

The containers 85 are placed into the pockets 55 78, 79 in any suitable manner as by means of a disc 88 located adjacent and moving tangentially of the turret 71. The can with cover while in the turret pocket is conveyed onto and over an arcuate stationary support or guide rail 91 which directs the can into a seaming turret 93. Here can and cover are positioned upon one of a series 60 of pads or platforms 95 carried by the seaming turret, each platform being directly associated and located in vertical alignment with a seaming head unit 97 also carried by the turret 93 and driven from a vertical shaft 98 or in other suitable manner in a counter-clockwise direction. It is while the can and cover are being carried around with the seaming turret that they are 65 lifted by the platform 95 and subjected to a seaming operation in the seaming head unit 97.

70 Reference has already been briefly made to the safety feature associated with the starting of the motor 21 which requires that the clutch 33 be disconnected from the power shaft 36 before the

motor begins its rotation. A collar 101 (Figs. 2 and 4) is slidably mounted on the shaft 36 and when moved longitudinally of the shaft compresses or releases the spring 39 and disconnects or allows connection of the drive in the clutch 33.

This collar is grooved in its outer periphery and a yoke 103 carries a pair of diametrically spaced pins 104 which engage loosely within the groove of the collar. This yoke 103 is pivoted on a vertical pin 105 (see also Fig. 1) carried in 10 a bracket formed as an integral part of the extension cap 51. One arm of the yoke 103 carries a swivel 106 in which a rod 107 is adjustably secured.

15 The rod 107 is pivotally connected at 108 to an oscillating disc 109 having movement upon a stud 111 threadedly secured in the cap 51. The disc 109 when moved into the position shown in Fig. 1 forces the yoke 103 toward the end of the shaft 36 and holds the collar 101 so that the clutch 33 20 has disconnected. The pivot point 108 is passed the dead center between the points 106, 111 and the spring 39 acting through the collar and yoke holds a screw 112, carried in a lug 113 formed in the disc, against a stop 114 on the cap 51.

25 Disc 109 carries a pin 116 on which is pivotally mounted one end of a rod 117 which is threadedly secured to a block 118. The block 118 is pivotally connected at 119 to an arm 121 formed as an integral part with a rock shaft 122 (Fig. 2). 30 This shaft has oscillating movement within bearing 123 projected outwardly from the housing cover 13 and in a similar bearing 124 projecting outwardly from the chamber housing 11.

The shaft 122 is oscillated by a hand lever 131 35 (Figs. 1, 2 and 3) which is secured to its lower end. This hand lever provides the manual control of the clutch 33 and its end is formed with a hand grip 132. The lever has an arcuate extension 133 on one side. In the unclutched position of the hand lever 131 as shown in Fig. 1, the motor 21 can be started.

40 Motor 21 is suitably wired in an electrical circuit which will be hereinafter fully described and these wires lead into a switch box 141 which has a start button 142 and a stop button 143. When the start button is engaged the switch in the switch box 141 is closed and electrical energy may be brought into the motor to cause its rotation. When the stop button is pressed the current flowing in the switch box 141 is interrupted and the motor comes to a stop.

45 A lever 145 (Figs. 1, 2 and 3) is pivoted at 146 to a tubular housing 147 which is formed as an integral part of a hollow shell 148 bolted at 149 to the chamber housing 11. An arm 151 of the lever 145 projects over the stop button 143 when the hand lever 131 is in unclutched position and a projection 152 formed on the end of the lever at such time rests over and against the end of the arcuate projection 133 of the hand lever.

50 This position of the lever 145 leaves the start button unrestricted (Fig. 3) and the hand lever 131 cannot be moved from its unclutched position as long as the projection 152 of the lever 145 55 is in the way. The motor can, therefore, be started by engagement of the switch button 142 and completion of the electric circuit through the motor.

55 The lever 145 is provided with a hand grip 153 and the part of the lever on that side of its pivot is heavier than the arm side 151 and gravity holds the lever to normally cover the stop button 143 unless prevented by lever 131. After the motor has reached its speed without load the lever 145 60

5

25

35

40

45

50

55

60

65

70

75

is manually swung from the position illustrated in full lines in Fig. 3 into the position illustrated by the broken lines in that figure.

With the extension 152 out of the path of the extension 133 of the lever 131 the latter is moved by engagement with its hand grip 132 and the clutch spring 39 then being released operates to connect the rotating sprocket 31 with the main shaft 63, this action starting the operation of the machine. In its raised position the lever 145 is held against further movement by a stop lug 155 formed on the lever striking a projection 156 of the housing 147.

It will be observed that as long as the lever 145 is out of engagement with the lever 131, its arm 151 covers the start button 142. If, therefore, the lever is moved to permit throwing in of the clutch by operation of the hand lever 131, the motor cannot be started. If there should be a failure of electrical energy or if anything happens to stop the motor, it and the entire machine might stop with the hand lever 131 in clutched position. The start button 142 being covered at such a time would then prevent restarting of the motor. To uncover the start button the clutch must be disengaged. This is the safety feature which prevents the starting of the motor under a load.

The electric motor 21 is preferably connected in a three-phase electrical system (Fig. 6) comprising lead wires *a*, *b* and *c* which preferably pass through a suitable service switch 161 and thence into the switch box 141. This switch box contains the start and stop buttons 142, 143 previously referred to but in the wiring diagram some of these elements have been spread out for the sake of clearness. A wire *d* leads from one side of the starting button switch 142 and connects with the wire *c*, the opposite side of the switch being connected by a wire *e* to an automatic four contact switch *f* one point of which is joined by a wire *g* to the motor 21.

An electromagnet 165 is carried in the switch box 141 and is associated, by a movable solenoid core or similar device, with the automatic switch embodying the contact points *f*. This switch is a spring-back or normally open switch. The magnet is joined by a wire *h* to the two wires, *a*, *b*, and by a wire *i* which joins with one side of the stop button switch 143. The opposite side of the switch 143 is joined to the wire *e*.

When the electromagnet 165 is deenergized the automatic switch is open at the contact points *f* and no energy is flowing into the motor 21 and the apparatus is idle. The start button 142 is normally open and if the machine is to be operated the button must first be depressed. The stop button switch 143 is closed at all times excepting when its button is depressed.

In starting the motor the service switch 161 is first closed in the lead lines *a*, *b*, and *c*, and then the start button is depressed. A momentary starting current flows from the line *c*, wire *d*, switch 142, switch 143, wire *i*, the electric magnet 165 and wire *h* back to the lead lines *a*, *b*.

This energizes the electromagnet 165 and closes the automatic switch at contacts *f*, leading the current into the electric motor 21, the current passing through wire *c* and wire *g* and through the wires *a*, *b* and wires *j*, *k*, to excite the fields of the motor and cause its rotation. As soon as the automatic switch is closed at the contact points *f*, a holding current is established which follows the same path as the start-

ing current only now it passes along the wire *e* instead of the wire *d*.

The start button switch 142 no longer is included and its immediate release by the operator in no way affects the operation of the motor. As long as the current flows in this manner the motor operates, the electromagnet 165 remaining energized and holding the automatic switch closed and connecting the wires *a*, *b*, *c* with the wires *g*, *j*, *k* leading into the motor.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. A container handling apparatus comprising a main drive shaft, an electric motor for rotating said drive shaft, a manually operated friction clutch interposed between said drive shaft and said motor for providing a driving connection, a manually operated starting switch for establishing an electric circuit supplying operating current to said motor, and means for preventing closing of said starting switch and through it starting of the motor when said friction clutch is in clutched position and providing said driving connection.

2. A container handling apparatus comprising a main drive shaft, an electric motor for rotating said drive shaft, a manually operated friction clutch interposed between said drive shaft and said motor for providing a driving connection, a hand lever for operating said friction clutch, a manually operated starting switch for establishing an electric circuit supplying operating current to said motor, a blocking device associated with said starting switch and having movement into one of two positions, one position preventing movement of said hand lever while permitting access to said starting switch and the other position of said blocking device permitting operation of said hand lever while preventing closing of said starting switch.

3. A container handling apparatus comprising a main drive shaft, an electric motor for rotating said drive shaft, a manually operated friction clutch interposed between said drive shaft and said motor for providing a driving connection, a manually operated starting switch for establishing an electric circuit supplying operating current to said motor, and means obstructing said starting switch when said clutch is in driving engagement with said shaft, said means being operative to permit actuation of said switch after said clutch has been manually released from engagement with said shaft.

4. A container seaming apparatus which comprises, in combination, a seaming mechanism, feeding devices for conveying cans and covers into said seaming mechanism, a drive shaft for actuating said seaming mechanism and said feeding devices so that the covers are seamed to the cans, an electric motor for rotating said drive shaft, a manually operated friction clutch mounted on said drive shaft for providing a driving connection between said motor and said shaft, an electric switch electrically positioned in the electric circuit passing through said motor and having start and stop controls, and means associated with said friction clutch and dependent upon its

unclutched or clutched condition for preventing operation of either of the said start or stop switch controls so that the former can be actuated only when there is no driving connection in said friction clutch and no load on said drive shaft and the said stop control can be actuated only when the said driving connection is made and the load is on said drive shaft.

5. A container handling apparatus comprising
10 a main drive shaft, an electric motor for rotating said drive shaft, a manually operated friction clutch interposed between said drive shaft and said motor for providing a driving connection, a manually operated starting switch for establishing
15 an electric circuit supplying operating current to said motor, and means obstructing the closing of said starting switch when said clutch is in driving engagement with said shaft, said means being automatically operative to permit access to said switch on movement of said clutch to release position.

20 6. In a container seaming apparatus including

a seaming mechanism, feeding devices for conveying cans and covers into said seaming mechanism, a drive shaft for actuating said seaming mechanism and said feeding devices so that the covers are seamed to the cans, an electric motor for rotating said drive shaft, a manually operated friction clutch mounted on said drive shaft for providing a driving connection between said motor and said shaft, and an electric switch electrically positioned in the electric circuit passing through said motor and having start and stop controls: the combination with said mechanism of means associated with said friction clutch for alternately preventing access to the said start and stop switch controls so that the former can be actuated only when there is no driving connection in said friction clutch and no load on said drive shaft, and the said stop control can be actuated only when the said driving connection is made and the load is on said drive shaft.
